UNITED STATES PATENT OFFICE.

WILLIAM F. COOPER, OF NORWALK, OHIO, ASSIGNOR TO THE A. B. CHASE COMPANY,
A CORPORATION OF OHIO.

PLAYER GRAND PIANO.

967,330.

Specification of Letters Patent. Patented Aug. 16, 1910.

Application filed February 11, 1907. Serial No. 356,701.

To all whom it may concern:

Be it known that I, WILLIAM F. COOPER, a citizen of the United States, and a resident of Norwalk, in the county of Huron, State 5 of Ohio, have invented a certain new and useful Player Grand Piano, of which the following is a specification.

My invention relates to mechanical musical instruments and more especially to a 10 player grand piano, and involves the provision of means by which a grand piano may be either played in the usual manner or mechanically.

Generally speaking, it is the object of my 15 invention to provide a grand piano with attached playing mechanism, the whole being constructed and arranged so that the playing mechanism will not injure the appearance of the piano, and so that the addition 20 of the playing mechanism will not require changes in the form or construction of the piano proper or interfere with convenient repair and adjustment of the piano.

On the other hand, it is an object of my 25 invention to provide an apparatus in which the player mechanism is normally secured to the piano frame or casing, while being readily removable therefrom to permit convenient adjustment or repair of the player 30 mechanism. In building pianos, and especially grand pianos, it is of very great importance that the apparatus have, as a whole, an artistic appearance, so that in applying playing mechanism to such a piano one is obliged 35 to meet something more than the ordinary problems relating to convenience, economy and efficiency. The apparatus must work well and must be arranged so as to be readily repaired and adjusted, but in addition, it

40 must be so arranged as not to interfere with the artistic appearance of the piano. Thus the problem of providing an acceptable and an efficient player grand piano is rendered difficult by the necessity that the maker is 45 under to sacrifice none of the efficiency of the standard grand piano and to sacrifice none of its capacity for ready repair and adjustment, while providing a playing mechanism of the most efficient kind, and also readily 50 repairable and adjustable, without substantially altering the appearance of the piano. Thus it is desirable, and one of the specific 55 features of my invention, that the key-board and piano action may be readily removed from the piano by moving it horizontally

forward from the key-bed, and I have, therefore, so arranged and combined the player mechanism with the piano as to permit this to be done.

In accomplishing the objects of my invention I have disposed the principal parts of the mechanism of a pneumatic player horizontally and have secured them together in a relatively shallow structure independently of the piano casing and then secured that 60 structure beneath and back of the key-board so that no part of it, except certain connections to the treadles, extends far below the key-bed of the piano. I have arranged the apparatus to be divisible into two main 65 parts. One part comprises the piano casing and all of the ordinary piano parts except the pedal support and pedals, while the other part comprises the player mechanism and the pedal support and pedals connected 70 together independently of the piano and secured as a unit to the piano casing. This separable portion of the apparatus connects with the piano action through operating members extending upwardly through the 75 key-bed of the piano. When the player and pedal support are secured to the piano the pedal support is a substantial distance above the floor level. When it is desired to remove the player, for purposes of repair or adjust- 80 ment, the player is detached from the piano casing and is lowered to the floor level. This brings all parts of the player mechanism below 85 obstructing portions of the piano and permits the player mechanism as 90 a whole to be moved horizontally from under the piano.

My invention involves generally the features above set out and in addition thereto more specific features of construction and 95 arrangement which are described with their incumbent advantages more fully herein-after; as are also certain preferential features of my invention.

One specific embodiment of my invention 100 is illustrated in the accompanying drawings.

Figure 1 of these drawings is a longitudinal section through the player and through the front portions of the piano, the section being taken on the line 1—1 of Figs. 2 and 5; 105 Fig. 2 is a front view, the tracker box and its connections being removed, portions of the keybed being broken away and the keys and piano action being removed; Fig. 3 is a view from the left-hand side of the front 110

part of the piano casing and of the whole of the player, the separate casing or screen thereof being shown in section; Figs. 4 and 5 are top plan views of the left and right hand halves of the player detached from the piano; Figs. 6 and 7 are views of the right and left hand halves respectively of the player partly in section and looking upward on the line 6—7 of Fig. 1; Fig. 8 is a detailed sectional view on an enlarged scale of the tracker box, key bed and some of the operating connections, the forward portions of the figure being taken on a line near the center of the piano, while the rear portions of the figure are taken on a line at one side of the piano; Fig. 9 is a detailed sectional view of the pedal support and certain of the operating connections; and Fig. 10 is an enlarged plan view of several of the power 20 pneumatics and operating connections therefrom.

One result attained by my invention is that the piano casing and the ordinary parts of the piano have not been altered in form or appearance or their relation with each other in order to combine with them the parts of a player mechanism. These parts comprise a piano casing A supported from legs, one of which is shown at A', Fig. 2. A² is the sounding board supported and disposed in the usual manner within the casing below the strings A³. B is the keybed of the piano. Upon this keybed the piano action rests loosely in the usual manner so that it may slide transversely when the soft pedal is operated, and may slide forwardly when it is to be taken out of the piano for repair or adjustment. The piano action includes the keys C, the frame C' and the casting C² carrying the action parts as clearly indicated in Fig. 1. As is usual with grand pianos when the piano action is to be removed, the fall board A⁴ is detached from the casing as well as the key rail A⁵, thus removing all 45 obstructions to the forward movement of the action.

Referring further to the usual grand piano parts, a represents one of a series of dampers resting upon the several strings and adapted to be moved upward from the strings by the movement of the hinged damper rail a' operated from the right-hand or sustaining pedal. The particular connections between this pedal and the 55 damper rail have been modified in the present construction as will be explained hereinafter.

From each key there projects downward a wire d which is threaded and fits a corresponding thread in the key so that each of these wires may be independently adjusted, and upon each wire is secured a nut d'. It is by the engagement of the moving parts of the player with these nuts d' that the 65 piano action is operated by the player.

These wires are secured to the keys at the rear ends thereof and are to operate the action by imparting an upward movement to the rear of the key. In order to limit the upward movement of the key I have provided a rail secured to the casting C² and I carry by this rail a number of stops c², one above each key, which stops are carried on the ends of threaded wires c', each secured into threaded orifices in the rail. Each stop is therefore individually adjustable in position. It will be understood that in the manual playing of the piano the stop c² at the forward end of the key is sufficient, but I have found that the additional individual adjustable stops that I have described above the keys and back of the pivotal points thereof to be desirable when the player acts upwardly from the rear end of the keys.

E represents the bellows mechanism of the pneumatic player. It is operated from the treadles E' through mechanical actuating connections indicated in Fig. 1. The treadles E' are hinged at their rear ends to rods e' which are pivotally secured at their free ends to the lower ends of vertically disposed levers E². These levers are pivoted at e in a bracket secured to the lyre or pedal support F, and are thus in an unobtrusive position, being hidden from view from the front of the piano. The upper ends of these levers E² are connected to connecting rods E³ which operate bell cranks E⁴, whose free ends are connected by hinged arms E⁵ with members E⁶ connected to the movable parts of the bellows mechanism. The treadles are normally maintained in their upper position by the springs E⁷. The operative forward position of the treadles E' is fixed by the rod e² which is hinged at e³ to the forward end of the treadles and is mounted at its other end in a hinged support at e carried by the pedal support F. The lower end of the rod e' moves in a nearly horizontal line from a position within the pedal support and below the hinge e³ to a position back of the pedal support. In order that the treadles and the rods e' may be thrown up to a forward position within the pedal support when desired, and without necessitating any preliminary pressing down of the treadles against the springs E⁷, I have constructed these parts as above described and have also so arranged the 120 lengths of the treadles E', the rods e' and e² and the vertical distance between the point e⁴ and the lower end of the rod e' as to make this movement possible. Thus the length of the rod e² added to the vertical 125 distance between e⁴ and the lower end of rod e' is equal to the sum of the lengths of the treadle E' and the rod e'. By this construction and these relative dimensions it is only necessary for the operator desiring to 130

use the piano for manual playing, to lift upon the outer end of the rod e^2 regardless of the respective positions of the treadles and the various parts will fold within the 5 pedal support, being vertically disposed therein (see Fig. 9).

It will be understood that the structure comprising my invention includes the usual parts of a pneumatic player. Such parts 10 are performing the usual functions of such a player and the several parts coöperate together to produce the proper movement of the power pneumatics in the usual way. I therefore shall not attempt to describe the 15 specific construction of each of these various known parts or their pneumatic connections with other of these known parts.

The power pneumatics are placed below the keybed of the piano and closely adjacent thereto. The power pneumatics are 20 in two parallel lines extending across the piano, the several pneumatics of one series being reference lettered G and those of the other series being reference lettered G^2 . All the pneumatics are in the same horizontal plane and all are disposed horizontally, the pneumatics of one series being 25 set hinge to hinge with those of the other series. Each pneumatic is to act upon one 30 of the keys by imparting movement to the nut d' before described. To this end there is a vertical passage B' in the keybed of the piano just below the rear ends of the keys. The center line between the two series of 35 pneumatics is back of the center line of this passage in order, as will appear, to leave as much room at the front of the pneumatics as possible for the tracker box and motor. By placing the pneumatics horizontally and 40 hinge to hinge in this manner I am enabled to place them very close to the lower surface of the keybed and thus assist in rendering the player compact and in locating it in a relatively obscure position. The 45 movable part of each pneumatic is connected to one end of a hinged diagonal lever g , the hinge of the lever being in a bearing g' on a fixed support G^2 secured beneath the 50 passage B' to the keybed. The free ends 55 of the several hinged levers g are secured to the vertical wires or pitmen h , upon the top of which nuts h' are screwed so that each wire h with its nut h' constitutes an extensible upwardly extending member and each of these members is located so as to engage the nuts d' carried by the key which the particular pneumatic is to operate. When, therefore, the air is exhausted from 60 any pneumatic the upper side of that pneumatic is drawn down pulling down one end of the corresponding hinged lever g and pushing upwardly the other end thereof with the upwardly extending member secured thereto. One or both of the nuts d' and h' should be capped with felt or other 65

non-resonant material. The various keys are therefore operated by the movement of the upwardly extending members in the passage from the keybed, this movement being caused by the movement of the diagonal levers extending in opposite directions from the pitmen h to the pneumatics of the two series. Each pneumatic operates a key at one side of the pneumatic. 70

The power actuating members extending through the upward passage in the keybed should be properly guided in their movement and to effect this I have provided the slide h^2 having an opening through which the nut h' passes and secured within the passage B' of the keybed from a suitable support G^2 . By placing the guide within the passage B' I am enabled to locate the power pneumatics closely adjacent to the lower surface of the keybed and thus contribute to the compactness and unobtrusiveness of the player that is so necessary in use with a grand piano. 75 80 85

By the construction I have thus far described, I am able to adjust the point of engagement between the nuts d' and h' at the exact level of the top surface of the keybed. It is not desirable that this point of engagement be below such surface because then the piano action could not be removed 90 without moving all the keys, and it is not desirable to have the point of engagement above the level of the keybed because this increases the downward movement of the player necessary before it can be removed 95 from the piano. Moreover, it is desirable for purposes of accurate adjustment of the piano action to have this point of engagement accurately at the level of the top of the keybed. This feature of my invention, 100 therefore, enables me to apply the player mechanism accurately to the piano action and without adding any construction that prevents the desired movement of the piano action horizontally from the keybed. 105 110

H is a casing located below the power pneumatics and which contains the pneumatics that are controlled from the tracker box and which in turn control the power pneumatics. Preferably the pneumatics in casing H comprise primary and secondary pneumatics. The ducts from the tracker box to the pneumatics in casing H and the ducts from the pneumatics in casing H to the power pneumatics are in the pneumatic board H' located between the power pneumatics and the casing H. 115 120

I represents the tempo or controller box suitably connected by air ducts with the motor in the usual manner. J, J' are the expression bellows which are connected by air ducts with the power pneumatics and with the tempo or controller box. 125

K is the motor regulator or equalizer which is connected by air ducts with the bel- 130

lows E and with the tempo or controller box I.

These various controlling devices are located back of the keybed and at one side of the main bellows in substantially the horizontal plane of the bellows.

The tracker L connected to the ducts leading to the primary pneumatics by means of flexible tubes l' and fixed tubes l'' is carried 10 in a tracker box L' in which are the supports for the music roll L^2 and in which is also carried the take-up roll L^3 . This tracker box is hinged on pivots l so that it may be either placed in the operative or 15 playing position shown in Figs. 1 and 8, or may be swung downward under the keybed of the piano to the position shown in Fig. 3.

Upon the tracker box are mounted various 20 controlling levers to be manually operated while the player mechanism is in operation. At the right hand side is the lever m which operates a rock shaft m' , the rocking of which moves a connecting rod m^2 transversely operating a bellcrank m^3 from which a connecting rod m^4 is operated and connects to a valve in the tempo or controlling box I. Carried by the tracker box there is also a lever n to operate the damper rail. 25 This lever rocks the rod n' through which crank n^2 is operated to act upon the connecting rod n^3 . The movement of this connecting rod operates the bellcrank lever n^4 , the operation of which causes a downward 30 movement of the lever n^5 secured to the rock shaft n^6 upon the end of which is the crank n^7 which pushes up the connecting rod n^8 and engages and lifts the crank n^9 at the end of rock shaft n^{10} . The rocking of this 35 shaft n^{10} raises the upwardly projecting member n^{11} which bears on the under side of the damper rail a' . A movement therefore of the lever n through the connecting mechanism described lifts the damper rail a' and 40 removes the dampers a from the strings. This same result during the manual operation of the piano is achieved by bearing upon the right-hand pedal N, which is connected through a vertical rod N' with a bellcrank lever N^2 secured to the rock shaft n^6 before described. When the player together 45 with the pedal support and pedals is separated from the piano the connecting mechanism to the damper rail above described is 50 separated on the line n^{12} , where the connecting rod n^8 engages the crank n^9 , but when the various parts are assembled and secured together the connecting rod n^8 and crank n^9 55 register as described.

60 o and p are the expression levers carried by the tracker. These operate respectively the rock shafts o' and p' which are connected by rods o^2 and p^2 respectively to the bell crank levers o^3 and p^3 respectively. 65 From these levers there are rearwardly ex-

tending rods o^4 and p^4 which operate valves in the expression bellows J and J' . The three bell crank levers m^3 , o^3 and p^3 are secured one above another at one corner of the piano. The left-hand or soft pedal of 70 the piano O shifts the piano action transversely for the customary purpose. This pedal operates the vertical rod O' through which the rock shaft O^2 is operated. The rock shaft has a crank O^3 at its end through 75 which the vertical rod O^4 is operated. The movement of this rod O^4 operates the bellcrank lever O^5 , the free end of which enters a slot in the keyframe C' so that the downward movement of the pedal imparts a 80 movement of the keyframe to the right. When the player and the pedal support are removed from the piano, as hereinafter described, the connections between the pedal O and the keyframe are separated at the line 85 O^6 , where there is a loose engagement between the vertical rod O^4 and one end of the bellcrank O^5 .

It will be noted that the pedals are each 90 connected with vertical rods which operate rock shafts extending transversely in opposite directions beyond the pedal support and to opposite sides of the piano where they respectively operate the keyframe and the damper board. This enables these connections to be made without interfering with the space in the center of the piano and back of the pedal support in which the pneumatics, bellows, etc., are to be placed. The motor is also located beneath the keybed of 100 the piano, being at the right hand side of the piano in the present instance, and immediately in front of the pneumatics. The motor is indicated at P, its shaft being 105 shown at p' . This position of the motor is in conformity with the general objects of the invention in that it is closely adjacent to the under side of the keybed and in substantially the same horizontal plane as the remaining parts of the player, while being 110 located so that its shaft may be readily connected mechanically with the mechanism in the tracker box by means of the chain p^2 .

All of the parts of the player mechanism 115 are connected together and are connected with the pedal support independently of the piano casing. There is at each side of the player a side frame Q to which is secured both the main bellows and the pneumatic board II'. Running across the player and attached to the pneumatic board is a sill Q' (made hollow to form part of the air duct to the motor). Secured to this cross sill are the forwardly extending arms R at whose 120 ends are mounted the pivots l of the tracker box, the tracker box having a rearward extension L^4 mounted on such pivots. The motor is secured by the bracket r to one of the side bars Q and through a bracket i' 125 to one of the horizontally extending arms R. 130

The pedal support F is secured to the cross sill Q'. The pedal support, pedals and player are thus secured together independently of the piano casing and may be assembled and adjusted independently of the piano and constitute one of the two main parts of the apparatus. This main part is secured to the piano in a position shown in the drawings. On the forwardly extending arms R are lugs R' through which pass thumbscrews R² which engage with a metal cross bar R³ let into the under side of the keybed of the piano. On the forward end of the side bars Q are brackets Q² through which are orifices q to receive similar thumbscrews which screw into the piano keybed or plates let into the same. Secured to the bellows board are two brackets T which act as a support for the pivots of the bell cranks F⁴. These brackets have orifices to receive thumbnuts which screw into a plate T' which is attached to the arms of the spider of the piano. It will thus be seen that the player and pedal supports are detachably secured to the piano by the six thumbscrews described.

When it is desired to remove the player from the piano it is only necessary to loosen these thumbscrews and the player may be lowered until the pedal support rests upon the floor. This only needs a movement equal to about the thickness of the keybed for none of the fixed parts of the player extend above the keybed, the highest fixed points of the player being the bracket T and the nuts h'. When, therefore, the player has been lowered to this position it may be moved horizontally backward from beneath the casing of the piano.

V represents a casing or screen which is secured to the side frame of the player and surrounds the back portion of the same so as to hide the bellows and other portions of the mechanism from view. The upper edge of this screen extends a less distance above the lower edge of the surrounding piano casing than that which separates the pedal support from the floor so that when the player is detached and lowered the screen may be moved horizontally from under the casing.

Additional supports for the player when it is detached from the piano are provided in the form of legs W which are hinged to the player at w and ordinarily lie horizontally within the casing.

In order that the movable supports of the player may accurately register with the movable parts of the piano action, I have provided dowels x which project upward from the side bars Q and enter recesses formed in the keybed of the piano. These dowels projecting upwardly from the player guide the player to the exact position which it should occupy with relation to the piano.

I have throughout referred to the appa-

ratus described as a player grand piano and my invention broadly and specifically is peculiarly applicable thereto, since a number of problems are met with in the practical development of grand pianos that are different from those met with in the application to upright pianos, while some of these problems are different when applied to what are generally known as square pianos. It will be understood, however, that I do not mean by the expression grand piano to necessarily limit myself to the precise form and detail of pianos that are now known as grand pianos, but desire to include within the claims apparatus in which the particular form and details of the piano may vary in some respects from the present known types of grand pianos provided that the substantial combination and mode of operation of the claims are applicable thereto and embodied therein. I believe that I am the first to have developed a practical and commercial player grand piano in which are obtained the results necessary to a proper player grand piano without interfering with the artistic appearance and the capacity of adjustment and repair of the piano and of the player, and I, therefore, do not desire to be limited to the specific construction and arrangement which I have shown and described, my invention as set out in the appended claims being broader than such specific features.

Having thus described my invention what I claim as new and desire to protect by Letters Patent is:—

1. In a player grand piano, the bellows, expression and tempo boxes, motor and pneumatic action, secured together and disposed to form a relatively flat and thin structure, and means for securing said structure as a unit to the piano to lie horizontally partly beneath and partly back of the keybed of the piano.

2. In a player grand piano, the bellows, expression and tempo boxes, motor and pneumatic action, secured together and disposed to form a relatively flat and thin structure, and means for securing said structure as a unit to the piano to lie horizontally partly beneath and partly back of the keybed of the piano, the extreme upper portion of said unitary structure being at substantially the level of the top of the key-bed.

3. The combination with a grand piano, of a player, including bellows, expression and tempo-boxes, the pneumatic action, motor, tracker box, rolls, and suitable pneumatic connections and mechanical operating connections, means for securing all of said parts together independently of the piano casing, and means for securing said player as a unit to the piano as a horizontally disposed player structure.

4. The combination with a grand piano, of

a pneumatic player therefor having its various parts secured together independently of the piano casing, a pedal support secured to the player and having operating connections to the player, and means for securing the combined player and pedal support to the piano in operative relation with the piano action.

5. A player grand piano comprising two main parts, one part comprising the piano, including its strings, sounding board, keys, action and casing, the other comprising the player and the supports for the piano pedals, and detachable connections securing the two main parts together in operative relation.

6. A player grand piano comprising two main parts, one part comprising the piano, including its strings, sounding board, keys, action and casing, the other comprising the player and the supports for the piano pedals, and detachable connections securing the two main parts together in operative relation, the player parts being so disposed as to permit free separation of the two main parts 25 by a relative vertical and horizontal movement.

7. In a player grand piano, a main part including the piano casing, strings, sounding board, keys, action, controlling devices and 30 mechanical connections therefrom, another main part comprising the player parts, the pedal support, the pedals and actuating connections therefrom, and means for securing the two main parts together with the piano action in operative relation to the player and the pedal connections in operative relation to the mechanical connections from the controlling devices.

8. In a player grand piano, a player mechanism detachable from the main parts of the piano, a pedal support secured to said mechanism, controlling devices in the piano, and mechanical connections from the controlling devices and from the pedals, the two 45 sets of mechanical connections being positioned to register when the player mechanism is secured in operative position.

9. In a player grand piano, the combination with the piano of power actuated members secured beneath the key bed of the piano and extending upwardly through the key-bed, and operating members for the piano action carried above the key-bed of the piano, said power actuated members and action operating members loosely engaging each other along a line substantially at the upper level of the key-bed.

10. In a player grand piano, the combination with the piano of power actuated members secured beneath the key-bed of the piano and extending upwardly through the key-bed, operating members for the piano action carried above the key-bed of the piano, said power actuated members and action operating members loosely engaging

each other along a line substantially at the upper level of the key-bed, and means for individually adjusting the point of engagement between each power actuated member and the corresponding action operating member.

11. In a player grand piano, the combination with the piano of power actuated members secured beneath the key-bed of the piano and extending upwardly through the key-bed, operating members for the piano action carried above the key-bed of the piano, said power actuated members and action operating members loosely engaging each other along a line substantially at the upper level of the key-bed, means for individually adjusting the position of the engaging ends of the power actuated members, and means for individually adjusting the engaging ends of the action operating members.

12. In a player piano, the key-bed thereof power pneumatics secured below the key-bed, adjustably extensible members operated by said pneumatics extending upward through the key-bed, and adjustably extensible members secured to the several piano keys and extending downward to engage the pneumatically operated members.

13. In a player grand piano, the combination with the piano and its action and key-bed of two series of power pneumatics each arranged horizontally beneath the key-bed, the members of each series lying side by side in two parallel lines extending across the piano, and members operated by the several pneumatics extending upwardly through the key-bed.

14. In a player grand piano, the combination with the piano and its action and key-bed of two series of power pneumatics each arranged horizontally beneath the key-bed, the members of each series lying side by side in two parallel lines extending across the piano, the members of one series lying hinge to hinge with the members of the other series, and members operated by the several pneumatics extending upwardly through the key-bed.

15. In a player grand piano, the combination with the piano and the keys and keyboard thereof, having a passage therethrough beneath the keys, of downwardly extending members secured to the several keys above said passage, upwardly extending members passing through said passage and engaging the downwardly extending members, power pneumatics, each horizontally disposed beneath the key-bed, lying side by side in a line extending across the piano, and connections between said pneumatics and the several upwardly extending members.

16. In a player grand piano, the combination with the piano and the keys and key-

board thereof, having a passage therethrough beneath the keys, of downwardly extending members secured to the several keys above said passage, upwardly extending members passing through said passage and engaging the downwardly extending members, two series of power pneumatics extending across the piano beneath the key-bed, the members of each series lying side by side and the members of one series lying end on to the members of the other series, and connections between the individual pneumatics and the several upwardly extending members.

15 17. In a player grand piano, the combination with the piano and the keys and key-board thereof, having a passage therethrough beneath the keys, of downwardly extending members secured to the several 20 keys above said passage, upwardly extending members passing through said passage and engaging the downwardly extending members, two series of power pneumatics extending across the piano beneath the key-bed, the members of each series lying side by side and the members of one series lying 25 hinge to hinge with the members of the other series, and connections between the individual pneumatics and the several upwardly extending members.

18. In a player grand piano, the combination of player actuated members beneath the key-bed of said piano and extending upwardly through the key-bed to substantially 35 the upper level of said key-bed, and piano actuating members contacting with said player actuated members at substantially the upper level of said key-bed.

19. In a player grand piano, the key-bed 40 having a vertical passage therein, vertically movable action operating members passing upward through said passage, a transversely extending support beneath said passage, a series of power pneumatics lying on each 45 side of said support and a lever secured to each pneumatic pivotally mounted upon said support and connected to one of the action operating members.

20. In a player grand piano, the keys 50 thereof and the key-bed having a vertical passage below the rear ends of the keys, two series of power pneumatics beneath the key-bed, the members of one series lying end to end with the members of the other series, 55 the center line between the two series being back of the center line of said passage, and operating connections from the several pneumatics passing upward through said passage to said keys.

60 21. In a player grand piano, the piano keys, the key-bed with a vertical opening beneath the rear of the keys, two series of horizontally disposed power pneumatics beneath the key-bed and with the center line 65 between the series located rearward of the

center line of said passage, vertically movable key actuating members extending upward through said passage, and pivoted levers connecting the key actuating members alternately with the pneumatics of the different series.

22. In a player grand piano, the keys and the key-bed having a vertical passage beneath the keys, key actuating members in said passage, two series of power pneumatics 70 below the key-bed, each pneumatic being laterally displaced with relation to its key, and diagonal hinged levers extending alternately forward and backward from the key actuating members to the pneumatics of the 75 two series.

23. In a player grand piano, the combination with the keys and the key-bed having a passage therethrough, downwardly extending members screwed to the keys, pneumatically operated threaded members secured beneath the key-bed and passing upwardly into said passage and nuts screwed upon the threaded ends of said members and loosely engaging the downwardly extending 90 members.

24. In a player grand piano, the combination with the keys and key-board having a passage therethrough beneath the keys, of downwardly extending members secured to the several keys above said passage, upwardly extending members passing through said passage and engaging the downwardly extending members, power pneumatics, each 95 horizontally disposed and all in the same 100 horizontal plane closely adjacent to the bottom of the key-bed, and connections between said pneumatics and the several upwardly extending members.

25. In a player grand piano, the key-bed 105 and casing thereof, the piano action including the key-frame, keys and action parts movable horizontally forward upon the key-bed, the player detachably secured to the piano with operating members passing upward through the key-bed, said player being movable downward from the key-bed 110 when detached, and downwardly extending members secured to the keys and engaging 115 said operating members.

26. In a player grand piano, the piano casing, strings, sounding board and piano action secured together to form a unitary structure, the player parts and means for securing the same together independently 120 of the piano to form another unitary structure, means for detachably securing the two structures together, and vertical projections on one of said structures fitting vertically disposed recesses in the other of said structures.

27. In a player grand piano, the piano casing, strings, sounding board and piano action secured together to form a unitary structure, the player parts and means for 130

securing the same together independently of the piano to form another unitary structure, means for detachably securing the two structures together, and upwardly projecting dowels on said player adapted to enter orifices in the key-bed of the piano.

28. In a player grand piano, the key-bed thereof, a player action below the same and suitable actuating connections therefrom to 10 the piano action, a bellows mechanism behind said action, a motor beneath the key-bed and in front of the player action, and a tracker box supported from a point beneath the key-bed and at one side of the 15 motor.

29. In a player grand piano, the key-bed thereof, the bellows mechanism and expression and tempo boxes secured at the rear of the same, the power pneumatics all disposed in the same horizontal plane forward of the 20 rear of the key-bed, and the motor below the key-bed and in front of the power pneumatics, a tracker box, and a movable mounting for the same at one side of the motor adapted to permit movement of the tracker 25 box from an obscure position beneath the key-bed to an operative position in the line of vision of the operator.

at a point below the key-bed and at one side of the motor.

25

30. In a player grand piano, the key-bed thereof, the bellows mechanism and expression and tempo boxes secured at the rear of the same, the power pneumatics all disposed in the same horizontal plane forward of the 30 rear of the key-bed, and the motor below the key-bed and in front of the power pneumatics, a tracker box, and a movable mounting for the same at one side of the motor adapted to permit movement of the tracker 35 box from an obscure position beneath the key-bed to an operative position in the line of vision of the operator.

In testimony whereof, I have signed my name to this specification, in the presence 40 of two subscribing witnesses.

WILLIAM F. COOPER.
